UNITED STATES PATENT OFFICE.

LOUIS BURMESTER, OF OMAHA, NEBRASKA.

AIR-HEATING FURNACE.

Application filed February 21, 1928. Serial No. 255,884.

The invention relates to air heating furnaces, particularly of the type shown in Patent No. 1,651,668 dated Dec. 6, 1927, and issued to me and A. Munroe jointly, and 5 has for its object to provide beneath the tube holding drum a chambered casing forming a combustion chamber in which is disposed a heating element, and tubes leading upwardly from said casing and discharging into the 10 lower side of the tube casing, whereby the heated air will circulate between the tubes in the tube casing, for heating the air circulating through the tubes.

A further object is to form the lower corner 15 of the tube casing flat and horizontally disposed whereby a relatively compact structure is formed and sufficient space provided for the combustion casing without materially adding to the height of the furnace as 20 a whole.

A further object is to provide bars at opposite sides of the combustion chamber casing for supporting said casing and terminating at their upper end in diverging portions 25 secured to the upwardly diverging sides of the tube casing.

A further object is to provide a main casing housing the tube and combustion chamber casing and provided with discharge 30 openings and with air intake openings through which fresh air passes, is heated in its passage through the tubes and is discharged.

With the above and other objects in view 35 the invention resides in the combination and arrangement of parts as hereinafter set forth, shown in the drawings, described and claimed, it being understood that changes in the precise embodiment of the invention may 40 be made within the scope of what is claimed without departing from the spirit of the invention.

In the drawing:

Figure 1 is a front elevation of the furnace, showing parts and tube casings broken away.

Figure 2 is a vertical longitudinal sectional view through the furnace main casing, shown the parts in side elevation.

Figure 3 is a perspective view of the combustion chamber casing and tube casing.

Referring to the drawings, the numeral 1 designates the main casing and 2 fresh air pipes leading into the main casing, and

55 through which fresh air pipes air passes into the casing 1, is heated by the device hereinafter set forth, then is discharged through the discharge openings 3 to the atmosphere or into pipes which may lead to any suitable point of discharge, for instance 60 the rooms of a house. Disposed within the main casing 1 adjacent its lower end is a combustion chamber casing 4, in which may be disposed any kind of heating element, however for purposes of illustration a gas 65 burner 5 is shown. In some cases it may be desirable to use an oil burner, an electric heating unit or some other type of heating unit, and it is to be understood that applicant does not limit himself in this regard. 70 Secured to opposite sides of the combustion chamber 4 are vertically disposed bars 6, which bars have their upper ends provided with upwardly diverging arms 7, which arms are secured to the opposite upwardly 75 diverging sides 8 of the tube casing 9, whereby it will be seen that the casing 9 is supported above the casing 4 and forms a single unit therewith, which can be readily placed within the main casing 1. In devices of this character heretofore used, the heating element has been placed in the lower corner 80 of the tube drum 9, as shown in my patent above referred to, however this has disadvantages as the tubes are too nearly in direct 85 contact with the flames, and require the use of too heavy material, and to overcome this difficulty the present device is primarily designed, that is to take the heating element out of the tube casing, and to accomplish 90 this result without materially adding to the height of the device, the lower corner of the tube casing 9 is cut away, thereby forming a horizontally disposed flat surface or wall 10, and the heat and products of combustion pass upwardly through the pipes 11, which connect the wall 10 and the casing 4, and are discharged into the tube casing 9 where they circulate between the crossed 95 tubes 12, thereby heating said tubes and 100 heating the air which passes through the tubes from the chamber of the casing 1, and consequently the fresh air which has been taken in through the pipes 2 passes upwardly, and thence through the discharge 105 openings 3. After the heated air has performed its function and cooled, it naturally falls and is discharged through the pipe 13 to a flue or other point of discharge.

The combustion chamber 4 at its rear end 110 is provided with a discharge pipe 14, which discharges into the tube casing 9, and is

preferably provided with a controllable closure member 15, which will allow passage of obnoxious or poisonous gases to the discharge pipe 13 when certain fuels are used, however the use of this pipe is optional according to the kind of fuel used.

From the above it will be seen that an air heating furnace is provided which is simple in construction, has its heating unit in a separate casing from the tube casing, and one wherein there is no danger of the products of combustion mixing with the heated air. It will also be seen that the device will heat a continuous flow of fresh air, and if desired would heat a recirculating flow of fresh air.

The invention having been set forth what is claimed as new and useful is:

1. An air heating furnace comprising a main casing, a tube carrying casing within the main casing, said tube carrying casing having diagonal corners in a vertical plane, a combustion chamber casing below the tube carrying casing; discharge pipes connecting the combustion chamber casing and the tube carrying casing, a discharge pipe connecting the rear side of the combustion chamber casing and the tube carrying casing and means for closing said last named pipe.

2. An air heating furnace comprising a main casing having intake and discharge openings, a tube carrying casing within the main casing and having tubes extending entirely through the same, said tube carrying casing being rectangularly shaped and having diagonal corners in a vertical plane, the lower corner being cut away thereby forming a flat wall, a combustion chamber casing below the tube carrying casing and pipe connections between the combustion chamber casing and the tube carrying casing whereby heated air will pass into the tube carrying casing.

3. An air heating furnace comprising a main casing having air intake and discharge ports, a tube carrying casing within the main casing, tubes in said tube carrying casing and extending entirely through the same in crossed relation, a combustion chamber casing beneath the tube carrying casing, a heating element in said last named casing, and supporting bars secured to opposite sides of the combustion chamber casing, said bars having their upper ends connected to the tube carrying casing in diverging relation.

In testimony whereof I hereunto affix my signature.

LOUIS BURMESTER.
